SOUND RECORDING AND REPRODUCING
DEVICE

Carl Wilhelm Nystrom, deceased, late of Karlstad, Sweden, by Henrik Fabian Stenman, administrator, Karlstad, Sweden

Application November 13, 1937, Serial No. 174,462

12 Claims. (CL 274—9)

This invention relates to sound recording and reproducing means and more specifically to sound recording and reproducing means having a turntable associated therewith.

In general, it is an object of the invention to provide a device of the character described, which will efficiently perform the purposes for which it is intended, which is simple and economical of construction, which can be expeditiously, conveniently and safely manipulated, and which can be readily manufactured and assembled.

Another object of the invention is to provide a device of the above type wherein the turntable may be separated from the motivating elements by a motion of the former and wherein such separation is brought about automatically and/or manually and/or at the end of a predetermined period and/or at a predetermined position of certain of the motivating elements; to provide such a device wherein resilient means, which are one of the means which cause the said separation, are also available to give resilient contact between the turntable and the elements motivating it; and to provide such a device wherein the motivating elements are caused to cease to motivate when said separation takes place.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Figure 1 is a vertical view of a device embodying one form of the invention, partly in section;

Fig. 2 is a plan view of the device shown in Fig. 1;

Fig. 3 is a view in elevation, partly in section, of the device shown in Fig. 1;

Figs. 4 and 5 show details of the device shown in Fig. 1;

Fig. 6 illustrates another embodiment of the invention; and

Figs. 7 and 8 are views, in elevation and in plan, of still another embodiment of the invention, with some parts omitted.

As shown in Figs. 1 and 2, the apparatus is provided with a base plate 1, carrying supports 2 for a shaft 3. The shaft 3 is connected with one arm of a carrier 4, preferably U-shaped, in which the pivot 10 of a turntable 8 is mounted 5 rotatably. The turntable is adapted to carry a record or a disc of wax. The other arm 5 of the carrier is provided with a member, say in the form of a roller 1, mounted on a spring-actuated pin 6, and adapted to engage a suitable operating member which, in the embodiment shown, consists of an eccentric 13. The eccentric is attached to an axis 12 mounted in supports 8. When the axis is rotated in one direction or the other, the carrier 4 will be lifted or lowered together with the turntable. The driving means of the turntable comprises a rotating friction wheel 11, which rotates the turntable by friction, and which, during the rotating movement, is displaced radially in relation to the said turntable. 20 The radial movement may be achieved by means of a screw, threads or another suitable device. A simple construction is disclosed on the drawings, according to which the friction wheel itself is provided with ribs, cams or grooves, which are 25 closed round the periphery and which, when the friction wheel engages the turntable, mesh with a helical groove arranged at the lower surface of the turntable. Due to this arrangement, the friction wheel will be fed to the center or the 30 periphery of the turntable and, at the same time, the friction wheel will rotate the turntable. If the friction wheel rotates at constant velocity of rotation, those points which are on the upper surface of the turntable and which are successively, 35 directly above the friction wheel will rotate at a constant linear velocity.

The friction wheel is combined with a guiding collar 14 and a journal 15, both being slidably mounted on a rod 16 supported in supports 17. 40 The journal 15 does not take any part in the rotation of the friction wheel. Special means may be provided in order to prevent the journal from rotating, e. g., comprising a guiding roller 34 combined with the journal and guided on a shaft 45 33 (Fig. 7). The rod 16 is rotated by means of driving means (not shown) connected to a transmission wheel 18. In order to cause the friction wheel to rotate and to be displaced along the rod 16, there may be arranged suitable means, 50 e. g., a pin or the like engaging an axial groove in the rod.

Instead of causing the friction wheel 11 to engage with the lower surface of the turntable, there may be arranged a special driving table 55

adapted to be rotated by the friction wheel and connected to the turntable in a suitable manner.

The recording means and the reproducing means together with the usual horn are not shown on the drawings. In the operation of the apparatus, the friction wheel is displaced radially in relation to the turntable, usually toward its center. At the same time, the recording member or the needle moves on the wax disc or the record, respectively, in the direction toward the center of the disc. For this purpose, the carrier of the recording member may be connected to the friction wheel or its guiding collar 14 or journal 15 in a suitable manner, but the needle is guided in the usual manner by the helical groove of the record.

After having recorded the wax disc or after having played the record, the friction wheel, which now has reached its inner position on the helical groove of the turntable, must be returned to its outer position in order to enable a new record disc to be played. For this purpose, it is necessary to release the friction wheel from its engagement with the lower surface of the turntable. According to the embodiment shown, this result is achieved by connecting the carrier 4 with a spring 24 attached at the base plate and acting to draw the carrier 4 upwardly. During the operation of the apparatus, the carrier and the turntable are pressed downwardly by means of the eccentric 13 against the action of the spring 24, but when it is desired to effect the release, the eccentric is rotated so that its cam releases the roller 1, whereby the spring 24 is caused to lift the carrier 4. (This position is shown on the drawings.)

Now the friction wheel may easily be returned to its initial position along the rod 16, and after there has been effected, by rotation of the eccentric, the lowering of the turntable so that it engages the friction wheel, the apparatus is ready for recording or reproduction of a new disc.

The spring 24 also effects resilient engagement between the friction wheel and the turntable during the operation.

When the apparatus is not in use, it is suitable to maintain the friction wheel in released position from the turntable. The space between these parts may be controlled by means of a set screw 25.

In order to enable the engagement and the release of the turntable from the friction wheel, the shaft 12 of the eccentric may be rotated manually or automatically as soon as the friction wheel reaches the position corresponding to the innermost spirals of the record. Figs. 2-4 disclose an embodiment of the automatic type, comprising an angular arm 19 pivoted to the base plate and preferably provided with rollers 20 and 21 at its ends. The roller 20 is arranged to project normally into the path of movement of any part which moves with the friction wheel, say a screw 22 (Fig. 3) attached to the journal 15, while the roller 21 is located close to a hook 23 attached to the shaft 12. If the friction wheel 11 is assumed to move inwardly to the center of the disc 9, the screw 22 will engage the roller 20 at a predetermined position of the friction wheel, so that the angular arm 19 is turned anti-clockwise, as seen from above, thus causing the roller 21, as it engages the hook 23, to rotate the shaft 12 and the eccentric 13 in such a direction that the carrier 4 together with the turntable 9 are lifted and the turntable is released from engage-

ment with the friction wheel under the action of the spring 24.

The end of the rod 16 may be provided with a handle.

It is desirable that the motor driving the friction wheel be stopped automatically when the friction wheel is released from its engagement with the turntable. According to Fig. 5, a projection is attached to the shaft 12 for this purpose. The said projection engages, in a predetermined position, a spring contact 51 cooperating with a fixed contact 52. The contacts 51 and 52 are either connected directly in the circuit of the electrical motor arranged for the rotation of the friction wheel, or in a relay circuit controlling the rotation of the motor. The arrangement is made in such a manner that the circuit of the motor is interrupted when the shaft 12 occupies a position in which the turntable is lifted from the friction wheel. The motor may also consist of a clockwork which may be actuated mechanically by the projection 50.

In order to facilitate the displacement of the friction wheel toward the center of the turntable 9, an arm of the non-rotatable journal 15 may be connected to a spring 26 by means of a wire 21, or the like, guided by a suitable roller. The spring 26 is attached to a suitable stationary part of the apparatus and is of a size sufficient to overcome the frictional resistance between the collar 14 and the journal 15 and the rod 16.

Fig. 6 shows an embodiment in which the carrier 4 may be lifted and lowered manually by means of an arm 28 provided with a projection 29 and combined with the arm 5 of the carrier, preferably by means of a spring 30. The dotted lines show the position of the arm when the turntable 9 has been lowered to engage the friction wheel, while the full lines show the released position.

Another embodiment is shown in Figs. 7 and 8. The eccentric 13 is provided with a cam, the length of which being such that at any position of the eccentric the cam engages either the roller 1 or a projection 32 mounted on the arm 5 above the eccentric. In the position shown on the drawings, the cam 31 engages the projection 32 so that the turntable 9 is lifted from the friction wheel. By this arrangement, there is avoided the shaking of the turntable 9 and the friction wheel 11 when they engage each other, e. g., during transport, which shaking may happen in the device according to Figs. 1-4 due to the elasticity of the spring 24. The turntable may be lowered to the friction wheel in the same manner as in the embodiment previously described.

In using records having diameters of different sizes, it is necessary to suit the initial position of the friction wheel at the outer portion of the turntable to the size of the record. To this purpose, an arm 35 (Figs. 7 and 8) is rotatably connected with journal 15, said arm being pivoted to an arm 36. The arm 36 is attached to a collar 37 which is journalled rotatably on a support 38, and which carries a pointer 39 above a fixed dial 40. This dial indicates the length of the diameter of the records by means of circular arcs or in another manner. If the pointer is rotated by means of a member 41 attached to the collar 37, the arms 35 and 36, the journal 15 and the friction wheel 11 are also moved. In this manner, the initial position of the friction wheel may be predetermined to suit the diameter of the record to be used.

If it is desired to use the apparatus for the re-

production or recording of the usual kind of records, which require a constant rotational velocity of the turntable, the radial displacement of the friction wheel must cease so that the said wheel is caused to operate at a constant radius. Figs. 7 and 8 show a device adaptable to this purpose. According to this embodiment, the angular arm 19 is arranged on a displaceable slide 42. When the slide occupies the position indicated by full lines in Fig. 7, the roller 20 is engaged by the screw 22 when the friction wheel reaches the inner spirals, but if the slide be displaced to the left, i. e., to the dotted position, the collar 14 and the friction wheel may be moved past the roller 20 so that they reach the innermost portions of the turntable 9 in which there are no helical grooves. The slide is guided by pins 43a and 44a, respectively, projecting into grooves 43 and 44, of which the latter has an angular shape so that the slide may be locked in the desired position under the action of a spring 45.

When the friction wheel 11 has been displaced to the center of the turntable 9 sufficiently far in order to give the turntable the desired rotational speed, the collar 14 should be locked in this position in order to prevent the friction wheel from moving radially. A suitable device for this purpose is also shown in Figs. 7 and 8. The right part of the slide 42 carries a vertical arm 46 provided with a projecting part 47 which, in the left position of the slide, is caused to engage a groove 48 on the collar 14.

The surface of the lower side of the turntable which the friction wheel engages when it is desired to effect constant rotational velocity of the turntable, may be provided with concentric grooves, in which the ribs of the friction wheel may engage. In this manner, the wear of these ribs is avoided.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described the invention, what is claimed as new and useful and desire to secure by Letters Patent is:

1. In a device of the character described, the combination comprising a turntable, movable means adapted for actuating said turntable, and automatic means adapted for moving said turntable away from said means when said movable means have moved to a predetermined position.

2. In a device of the character described, the combination comprising mounting means, a turntable pivotally mounted in said mounting means, means adapted for actuating said turntable, and automatic means adapted for moving said turntable and mounting means away from said actuating means when said actuating means are in a predetermined position of operation.

3. In a device of the character described, the combination comprising mounting means, a turntable pivotally mounted in said mounting means, means adapted for actuating said turntable, and automatic means adapted for moving said turn-

table and mounting means away from said actuating means after said actuating means have actuated said turntable at a predetermined speed.

4. In a device of the character described, the combination comprising mounting means, a turntable pivotally mounted in said mounting means, means adapted for actuating said turntable and means including a cam-like element and adapted to move said mounting means away from said actuating means, and means operated by said actuating means when said actuating means are in a predetermined position of operation and adapted to operate said cam means.

5. In a device of the character described, the combination comprising mounting means, a turntable pivotally mounted in said mounting means, means adapted for actuating said turntable, means including a cam-like element and adapted to move said mounting means away from said actuating means, means operated by said actuating means when said actuating means are in a predetermined position of operation and adapted to operate said cam means, and means adapted for causing said actuating means to cease actuating said turntable and operated by said cam operating means.

6. In a device of the character described, the combination comprising mounting means, a turntable pivotally mounted in said mounting means, means adapted for actuating said turntable, means including a cam-like element and adapted to move said mounting means away from said actuating means, means operated by said actuating means when said actuating means are in a predetermined position of operation and adapted to operate said cam means, and motive means for said actuating means and means adapted for rendering said motive means idle and operated by said cam operating means.

7. In a device of the character described, the combination comprising mounting means, a turntable pivotally mounted in said mounting means, means adapted for actuating said turntable, means including a cam-like element and adapted to move said mounting means away from said actuating means, and means operated by said actuating means when said actuating means are in a predetermined position of operation and adapted to operate said cam means, said cam-like element being adapted for raising said mounting means against the force of gravity away from said actuating means.

8. In a device of the character described, the combination comprising mounting means, a turntable pivotally mounted in said mounting means, means adapted for actuating said turntable, means tending to move said mounting means away from said actuating means, and cam means operated by said actuating means and preventing, at a predetermined position of said cam means, said mounting-moving means from moving said mounting means.

9. In a device of the character described, the combination comprising mounting means, a turntable pivotally mounted in said mounting means, means adapted for actuating said turntable, resilient means tending to move said mounting means away from said actuating means, and cam means operated by said actuating means and preventing, at a predetermined position of said cam means, said resilient means from moving said mounting means.

10. In a device of the character described, the combination comprising mounting means, a turn-

- table pivotally mounted in said mounting means, means adapted for actuating said turntable, means tending to move said mounting means away from said actuating means, cam means operated by said actuating means and preventing, at a predetermined position of said cam means, said mounting-moving means from moving said mounting means, and a frame, said mounting means being pivoted on said frame.
- 10 11. In a device of the character described, the combination comprising mounting means, a turntable pivotally mounted in said mounting means, a cam, a friction wheel adapted for actuating said turntable and movable along a shaft, said mounting means being movable and the motion thereof being controlled by said cam, an axle supporting said cam, a bell crank movable by said wheel during a portion of the wheel's motion along said shaft and adapted to rotate said axle.
- 15 12. In a device of the character described, the combination comprising mounting means, a turntable pivotally mounted in said mounting means, a cam, a friction wheel adapted for actuating said turntable and movable along a shaft, said mounting means being movable and the motion thereof being controlled by said cam, an axle supporting said cam, a bell crank movable by said wheel during a portion of the wheel's motion along said shaft and adapted to rotate said axle, and resilient means between said cam and said mounting means.
